ATTORNEYS

UNITED STATES PATENT OFFICE.

JAMES WILBERT MERTZ, OF AVANT, OKLAHOMA.

COIL BOX.

Application filed July 9, 1924. Serial No. 725,031.

To all whom it may concern:

Be it known that I, JAMES W. MERTZ, a citizen of the United States, and a resident of Avant, in the county of Osage and 5 State of Oklahoma, have invented a new and Improved Coil Box, of which the following is a full, clear, and exact description.

This invention relates to an improved coil box especially adapted for Ford cars and 10 Fordsons and has for an object to provide a construction wherein the various coils may be quickly and easily applied and removed at any time.

Another object of the invention is to provide a coil box formed with a removable side means for normally locking the same 15 in a closed position, the structure being such that when the side is moved out of the way, the coils may be adjusted, removed 20 and replaced quickly.

In the accompanying drawings—

Figure 1 is a perspective view of the improved coil box disclosing an embodiment of the invention, the same being shown filled 25 with the usual number of coils.

Figure 2 is a sectional view through Figure 1 approximately on line 2—2.

In coil boxes used on Ford cars and other places, it requires an appreciable time to remove any of the coils for repair or replacement. During different weather conditions, the coils have a tendency to expand and contract, whereby the various contacts may be affected, and also whereby it is difficult to 30 remove the tightly wedged coils. In order to permit a quick and easy adjustment of the coils and also a quick and easy removal and replacement, the improved structure embodying the invention has been provided.

Referring to the accompanying drawings by numeral, 1 indicates the coils, which are of the usual type, and 2 the body of the box, which is also of the usual type, having the lower series of contacts 3 and the 45 various outer contacts 4 co-acting with the coils 1. As the arrangement of contacts and also the arrangement of coils are old and well known, a detailed description thereof will not be given. The box 2 heretofore 50 has been made solid throughout except that it has been open at the top. In the present invention, the front wall 5 is supplied with hinges 6 and 7, whereby it may be hinged outwardly, as shown in Figure 2, whenever 55 desired and the coils quickly and easily moved laterally or tilted for movement lat-

erally or upwardly. In order to hold the ends of the box 2 in proper place, the front wall 5 is provided with flanges 8 and 9 which fit over the ends of the box 2 and hold the 60 same in place, whereby the coils 1 will always be maintained in correct position. Hinge members 10 and 11 are connected to opposite ends of the box 2, the parts being connected to the ends being identical but 65 the other sections, namely, sections 12 and 13, being constructed differently. Section 12 is provided with an offset enlargement 14 which carries a rod 15 rigidly secured thereto, said rod loosely passing through the 70 turnbuckle 16, the same being formed with an enlargement 17 whereby the turnbuckle 16 may freely rotate, but when moved longitudinally in one direction will pull rod 15 and firmly hold the hinge 10 in the position shown in Figure 1. A hook 18 is threaded into the other end of the turnbuckle 16 and co-acts with a ring or link 19 which is swingably connected with the catch 20. The catch 20 consists of a flat 75 bar link 21 having the end opposite link 19 pivotally connected at 22 to the lever 23, which lever is provided with a bifurcated end 24, the respective legs of said lever being pivotally connected at 25 and 26 to the 80 legs 27 and 28 of the section 13. The pivotal connection 22 is offset inwardly so that when the lever 23 is resting against the shoulder 29 the parts will have been moved past dead center and consequently will automatically remain locked in place. There is a slight resiliency in all these members, so that when it is desired to disengage the hook 18, lever 23 may be grasped by the 85 fingers of the operator and quickly turned over in a direction toward the left, as viewed in Figure 1. This will move the pivotal structure 22 past dead center outwardly and over toward the turnbuckle 16. When the parts are thus loosened, the link 19 may be 90 disconnected from hook 18 and the hinges 10 and 11 quickly swung outwardly, whereupon the side 5 may be swung downwardly, as shown in Figure 2. When this has taken place, the various coils 1 may be easily 95 moved out of the box as the ends are released, and also as the coils may be tilted toward the open side 5 until they are completely loose, they may be lifted out in substantially any desired direction.

I claim:

1. A coil box for Ford cars and the like

comprising a box structure provided with the usual contacts for co-acting with the coils to be applied thereto, said box structure having one side loose, hinge means for hinging said loose side in place, a pair of locking hinges connected to the ends of the box for locking the side in assembled position, and a plurality of means including a latch for holding said locking hinges in a locked position.

2. A coil box of the character described including a bottom, a side, a pair of flexible ends and a swinging side hinged to said bottom, said hinged side having a pair of flanges adapted to overlap said ends for holding the same in position, a pair of lock-

ing hinges, one hinge being connected with each of the ends and adapted to be swung around the front of said swinging side for locking the swinging side in assembled position, and manually actuated means for locking said locking hinges in locked heating position.

3. In a coil box, a swinging side, a pair of locking hinges for normally locking said side in assembled or closed position, a turnbuckle connected with one of said hinge locks, said turnbuckle being provided with a hook, and a catch connected with the other of said locking hinges formed with a link adapted to be looped over said hook.

JAMES WILBERT MERTZ.
